Primary Examiner — Kendra Leslie Hamilton*Assistant Examiner* — Jameson P Carey*(74) Attorney, Agent, or Firm* — Laurence P. Colton; Smith Tempel Blaha LLC(57) **CLAIM**

The ornamental design for a fastening tape with clip, as shown and described.

DESCRIPTION

FIG. 1 is a top, right perspective view of a fastening tape with clip, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top, front perspective view of a fastening tape with clip, shown in a condition of use for clarity of disclosure;

FIG. 9 is a top, rear perspective view thereof;

FIG. 10 is a top plan view thereof;

FIG. 11 is a bottom plan view thereof;

FIG. 12 is a front elevation view thereof; and,

FIG. 13 is a rear elevation view thereof.

In the drawings, the broken lines depict environmental subject matter and form no part of the claimed design.
